UNITED STATES PATENT OFFICE.

EDWARD L. CALEY AND JOSEPH A. READ, OF PHILADELPHIA, PENNSYLVANIA, ASSIGNORS TO GILBERT COMBS, JOHN BAWDEN, AND JOHN H. BAWDEN, OF FREEHOLD, NEW JERSEY.

DESIGN FOR A PORTABLE FIRE-PLACE GRATE.

SPECIFICATION forming part of Design No. 19,149, dated June 11, 1889.

Application filed January 9, 1889. Serial No. 295,890. Term of patent 7 years.

To all whom it may concern:

Be it known that we, EDWARD L. CALEY and JOSEPH A. READ, citizens of the United States, and residents at Philadelphia, Pennsylvania, have invented a certain new and original Design for a Fire-Place Grate, of which the following is a specification.

Our design for a fire-place grate is fully shown in the accompanying photographic illustrations.

Figure 1 is a view of the parts of the grate detached from each other, and Fig. 2 is a perspective view of the grate with the parts assembled.

The essential feature of the design is the elaborate scroll-like ornamentation of the back and sides and the general outline of the front plate.

The leading features of the design of the back plate are the two plain scrolls, each starting from the base and terminating at each side in a helix. At the base of the back plate is a floral line, and on a backing of lattice-work is a central vertical stem, from which radiate a series of leaves, some of which terminate in scrolls, the whole forming

a floral scroll design. The side plates have ornamentation of a substantially similar character. The front plate is composed of a series of vertical bars having lips at their upper edges, each of these bars being of an ornamental character, and ornamental scrolls connecting the bars at two points, forming two continuous lines from end to end of the plate.

We claim—

1. In a design for a fire-place grate, the design for the back and side plates consisting of the foliated and scroll ornamentation, substantially as shown and described.

2. The design for a fire-place grate, substantially as described, and as shown in and by the accompanying photographic illustrations.

In testimony whereof we have signed our names to this specification in the presence of two subscribing witnesses.

EDWARD L. CALEY.
JOSEPH A. READ.
